UNITED STATES PATENT OFFICE

148,331

DESIGN FOR A PULL TOY

Arnold H. Scheinman, Milltown, N. J.

Application August 21, 1946, Serial No. 132,688

Term of patent 3½ years

(Cl. D34—15)

To all whom it may concern:

Be it known that I, Arnold H. Scheinman, a citizen of the United States of America, residing in Milltown and State of New Jersey, have invented a new, original, and ornamental Design for a Pull Toy, of which the following is a specification, reference being had to the accompanying drawing, forming part thereof.

Fig. 1 is a rear perspective view of a pull toy showing my new design.

Fig. 2 is a front perspective view thereof.

I claim:

The ornamental design for a pull toy, substantially as shown.

ARNOLD H. SCHEINMAN.
